ELECTRIC LIGHT FIXTURE

Eugene R. Kulka, New York, N. Y., assignor to
 C. D. Wood Electric Company, Inc., New York,
 N. Y., a corporation of New York

Application March 8, 1939, Serial No. 260,502

3 Claims. (Cl. 173—358)

My invention relates to a new and improved electric light fixture.

One of the objects of the invention is to produce a fixture of simple and economical construction and having an improved ornamental appearance.

Another object of the invention is to provide a fixture which includes a metal skirt to which a reflector is connected by suitable suspension means, the fixture being designed so that the entire filament of the bulb is located below the mouth of the reflector.

Another object of the invention is to provide a fixture in which the metal skirt is connected to the body of the fixture by a removable threaded member which is made of insulating material.

Other objects of my invention will be set forth in the following description and drawing which illustrate preferred embodiments thereof, it being understood that the above statement of the objects of my invention is intended generally to explain the same without limiting it in any manner.

Fig. 1 is a vertical central section of a part of the improved fixture, the representation of the reflector being omitted.

Fig. 2 is an elevation of the device shown in Fig. 1.

Figs. 3 and 4 are respectively sectional views on the line 3—3 of Fig. 2 and on the line 4—4 of Fig. 1.

Fig. 5 is a side elevation showing the complete fixture, part of the representation of the reflector being omitted.

As shown in Fig. 1, the device comprises a rigid plug-body 1, which is made of porcelain or other suitable insulating material. This plug-body or plug-member 1 is provided at its bottom end with a rigid, integral and laterally enlarged extension 1a. Said extension 1a has a first top recess of cylindrical shape, and its inner vertical wall is reduced to form a second annular recess below said top recess. The well-known spun metal shell 2 is assembled with the porcelain body 1, above the extension 1a. The shell 2 is corrugated so as to provide the usual external thread, so that the body 1 and the shell 2 can be screwed into a suitable outlet. The shell 2 is provided with an inturned flange at the top thereof. This flange or shoulder abuts a shoulder of the porcelain body 1. A clamping washer 3, which can be made of metal or other suitable material, is located above the flange of the shell 2.

A pair of screws 4 have their shanks located in vertical bores of the porcelain body 1. The wash-

er 3 has tapped holes which are engaged by the threaded shanks of the metal screws 4. The heads of the metal screws 4 clamp the top flange of a second or female spun metal shell 5, so that the second shell 5 is held against the bottom wall of plug member 1. The lower part of shell 5 is corrugated to provide an internal and external thread. A central metal contact pin 6 has a head 6a which abuts the top of the porcelain body 1. The bottom end of the contact pin 6 is provided with the usual resilient contact 7, which is of the usual U-shape. The upper leg of the U abuts the bottom wall of the plug member 1. A metal skirt 8 is provided at its bottom with an upturned flange 9. At its top the metal skirt 8 is provided with an inturned flange. This inturned flange is provided with an upstanding integral lug 10, which enters a vertical notch of the extension 1a. The metal skirt 8 is therefore held against turning relative to the porcelain body 1.

The metal skirt 8 is clamped in position by means of a rigid clamping member 11, which is also preferably made of porcelain or other suitable insulating material. The inner vertical wall 15 of the clamping member 11 is threaded so that it can be screwed upon the exterior thread of the female shell 5.

At its top, the clamping member 11 is provided with a reduced extension 11a which enters the annular recess which is formed in the inner wall of the extension 1a. The inturned flange of the metal skirt 8 is thus clamped between the annular edge-wall of clamping member 11 and the adjacent lateral wall of extension 1a. The extension 11a extends above said clamping wall of clamping member 11. The bottom edge-wall of the clamping member 11 can be provided with two or more recesses, so that the clamping member 11 may be turned by means of a suitable tool to 30 clamp the inturned flange of the metal skirt 8 to the extension 1a. If desired, the clamping member 11 can be turned reversely so as to separate the same from the female shell 5 and thus make it possible to detach the metal skirt 8 from the extension 1a.

An extremely compact and slender construction is thus provided which is of very graceful appearance, because the skirt 8 directly abuts the extension 1a and its outer diameter is substantially equal to the maximum diameter of extension 1a. The outer wall of extension 1a is curved, so that skirt 8 appears to be an extension of the member 1a. The outer wall of skirt 8 preferably has the same color as extension 1a.

The metal skirt 8 is provided with a suitable number of perforations 12, which have reduced extensions 12a. The reflector R can be made of any suitable plastic or other material. Beaded 5 chains 14 are preferably used for connecting the reflector R to the member 8.

As shown in Fig. 4, each of these chains 14 has separate beads 15. The end bead 15 of a chain 14 can be inserted through one of the openings 10 12, and the chain 14 is then lowered into the extension 12a so that the wall of the member 8 is located between a pair of adjacent beads 15.

At its lower end, each chain 14 is provided with a bead 16, which is larger than the beads 15. The beads 15 can be passed through suitable holes which are provided in the reflector R, below the mouth thereof. The end beads 16 are too large to pass through the holes in the reflector. The top bead 15 is then passed through 20 a hole 12, and the top end of the chain is then lowered so that the wall of the member 8 is located between the two top beads 15.

The chain itself is of usual construction, in which each of the beads 15 has a thin extension 25 on which the next bead 15 is movably mounted.

No claim is made to the construction of the chain per se.

The lengths of the chains 14 are adjusted so that the entire filament of the bulb B is located 30 below the mouth of the reflector. The bulb B is provided with the usual shell which can be screwed into the female shell 5. For this purpose the bulb B is provided with a neck of sufficient length, as indicated in broken lines in Fig. 35

1. The shell of the bulb B is located at the top end of its neck, in the usual manner.

The screws 4 clamp the washer 3 against the top shoulder or flange of the member 2, in addition to clamping the inturned flange of the shell 40 5 against the bottom end-wall of plug member 1, so that the member 2 and the washer 3 and plug member 1 and shell 5 are held tightly in assembled position. The contact pin 6 is held 45 against longitudinal movement by the members 6a and 7. The annular extension 11a fits snugly in the annular recess of the member 1a, so that lateral movement of the member 11 is substantially prevented. This takes the lateral stress off the shell 5.

50 The upper end of shell 5 is located in the top recess of extension 1a and part of shell 5 depends below said extension 1a. The upper part of shell 5 fits snugly in said recess, and said fit can be a close or tight fit, if desired.

55 A strong and rigid assembly is thereby provided even though the shell 5 is the usual thin spun metal shell. The diameter of the skirt 8 is substantially equal to the outer diameter of the member 11, so that a graceful and ornamental effect is secured and all the inner parts are concealed. The height of the skirt 8 determines the size and wattage of the bulb B which can be used in the fixture. Since these bulbs come in standard sizes, a bulb of a predetermined wattage 60 has a neck of predetermined length. It is therefore impossible to insert into the fixture a bulb whose wattage is less than the predetermined wattage and the entire filament of said bulb is located below the mouth of the reflector R, thus preventing unpleasant glaring light.

70 The member 1 and its integral skirt 1a is rigid and the member 11 is also rigid. The use of rigid members which are preferably made of porcelain or the like is superior to the use of yieldable fibre insulating members. Likewise 75 the member 1 and its skirt 1a and the shell 11

provide all the necessary insulation for the device.

It is not necessary, although it is preferable, for the member 11 to clamp the flange of the skirt 8 rigidly against the member 1a, because the lug 10 and the notch in the member 1a prevent the skirt 8 from turning relative to the member 1a.

For convenience the device is described and claimed with reference to the vertical position shown in the drawing. However the elements 10 shown in Figs. 1 and 2 may be used independently of the reflector. Likewise the longitudinal axis of the device shown in Figs. 1 and 2 may be held at any angle to the vertical.

It will be noted that the member 1 has an 15 upper reduced end.

The shells 2 and 5 are shown as being threaded, in order to conform to standard American practice. However a bayonet joint could be used without departing from the invention. 20

I have shown a preferred embodiment of my invention, but it is clear that numerous changes and omissions can be made without departing from its spirit.

Of course the contact pin 6 does not make electrical contact with the screws 4 or with the second metal shell 5. 25

Said pin can be replaced by any means for providing plug 1 with inner and outer contact means, in addition to shells 2 and 5. Hence, 30 whenever I specify said contact pin in a claim or claims, the claims are not limited to the use of said pin.

The metal shell 2 is electrically connected to the metal shell 5 by means of the metal screws 4 35 which are electrically connected to the inturned flange of the shell 5, and the metal washer 3. The pin 6 is spaced from both shells 2 and 5. Therefore, when the head of the bulb is screwed into position as indicated in Fig. 1, the circuit 40 is completed through the filament of the bulb in the usual manner. Of course metal rivets or eyelets could be used instead of the screws 4. The inner wall of the skirt 8 is made of smooth and reflecting metal or other material. This 45 opaque metal or skirt 8 prevents the light from being reflected outwardly from the neck of the bulb. Said light is reflected downwardly on the inner surface of the reflector R. The skirt 8 covers the entire neck of the bulb. If desired, 50 the skirt 8 could be shaped so as to cover the bulb up to the mouth of the reflector R. However for practical purposes it is sufficient if the skirt 8 downwardly reflects the light which otherwise would be passed through the wall of 55 the neck of the bulb. Maximum illumination and minimum glare are thus secured.

In the specific embodiment disclosed herein, the metal screws 4 are means which will fill the double function of holding the shell 5 in position 60 and electrically connecting the shell 5 to the shell 2. It would not be departing from this invention if this single means were replaced by separate means.

65 I claim:

1. A rigid plug member having a bore and having a laterally enlarged extension at its bottom end, a metal plug shell located on the outer vertical wall of said plug member, said extension having an upper recess and a lower recess of greater internal diameter than the inner diameter of the upper recess, a second metal shell 70 depending below said extension and having its upper end located in said upper recess, a contact pin located in said bore and insulated from 75

said shells, means connecting the second metal shell to said plug member and electrically connecting the second metal shell to the plug shell, said depending portion of the second metal shell being externally and internally threaded, a holding member made of insulating material and engaging the outer thread of the second metal shell and having a reduced top projection which is located in said lower recess, a skirt having an 5 inturned flange which is clamped between a portion of said holding member and said extension, the skirt depending below said holding member, the skirt having an upstanding projection which is located in a recess of said extension.
